Patented Oct. 17, 1916.

THE NORRIS PETERS CO., PHOTO-LITHO., WASHINGTON, D. C.

UNITED STATES PATENT OFFICE.

EMANUEL M. SHORTER, OF EMPIRE, ALABAMA.

SAFETY-HOLDER FOR COAL-CAR CHECKS.

1,201,987.

Specification of Letters Patent. Patented Oct. 17, 1916.

Application filed January 17, 1916. Serial No. 72,618.

To all whom it may concern:

Be it known that I, EMANUEL M. SHORTER, a citizen of the United States of America, residing at Empire, in the county of Walker 5 and State of Alabama, have invented certain new and useful Improvements in Safety Holders for Coal-Car Checks, of which the following is a specification.

This invention relates to new and useful 10 improvements in safety check holders, and is particularly adapted for use in coal mining and like industries.

The usual custom in the mining industry is to pay the miners by the load, or in other 15 words, by the cars which they mine and load, the miner attaching to the car when forwarding the same from the mine, a check bearing his name or other identification, in order that the weighing master may give the 20 credit for the car to the proper party. Heretofore, these checks have been hung loosely on hooks or placed in boxes or other suitable receptacles carried by the cars, and on frequent occasions, they have been lost, and 25 maliciously substituted by checks belonging to other miners who would thus receive the credit for the car.

The primary object of this invention is to provide a suitable check holder from which 30 the checks cannot be lost or substituted during the passage of the cars from the mines to the weighing master, the latter being provided with a suitable key or means for unlocking the holder and removing the checks 35 therefrom.

Another object of the invention is to provide a device of this character which will be simple, strong, durable and inexpensive to manufacture, efficient and reliable in operation, and well adapted to the purpose for 40 which it is designed.

With these and other objects in view, the invention consists of certain novel features of construction, and the combination and arrangement of parts as will be hereinafter 45 fully described and claimed.

In the accompanying drawings in which similar reference numerals indicate like parts throughout the several views: Figure 50 1 is a perspective view of a device constructed in accordance with this invention showing it attached to the side of a mine car; Fig. 2 is a side elevation of the interior casing of the device, the exterior covering thereof being broken away; Fig. 3 is a vertical sectional view through the interior casing of the

device; Fig. 4 is a vertical sectional view taken on the line 4—4 of Fig. 2; Fig. 5 is a transverse sectional view taken on the line 5—5 of Fig. 2; Fig. 6 is a similar view taken on the line 6—6 of Fig. 3; Fig. 7 is a similar view taken on the line 7—7 of Fig. 3; and Fig. 8 is a perspective view of the interior faces of the front and rear sides of the interior casing of the device.

In the present exemplification of this invention, an upright casing 1 is shown composed of a rear side 2 having flanges 3 extending laterally forwardly from the edges thereof, and a front side 4, the latter being secured to the rear side 2 by suitable bolts or screws 5, which may be extended beyond the plane of said rear side to attach the casing 1 to a suitable support. The front edges of the upper and lower end flanges 3 are provided with notches 6 which form slots 6' in connection with the front side 4, said slots 6' being of a sufficient size to allow the passage therethrough of the miner's checks with which this invention is particularly adapted 65 to be used.

The inner faces of the front and rear sides 2 and 4 are provided with raised portions 7 and 8 respectively, the edges of which curve inwardly from their central portions and 70 then outwardly to form flared ends 9 and 10 respectively of the raised portions 7 and 8. The thickness of the raised portions 7 and 8 varies between their respective ends, the ends 9 of the raised portion 7 being 75 greater in thickness than the central portion thereof, while the ends 10 of the raised portion 8 are thinner than its central portion. By this arrangement, it may be seen that there is formed a channel 11 which is 80 curved tortuously transversely of the casing 1. This tortuous channel extends longitudinally of the casing 1 from end to end of the same and has its ends in communication with the beforementioned slots 6'. Disposed within the casing 1 and extending 85 longitudinally of the same is a pair of spaced resilient arms 12, the inner sides thereof being disposed adjacent the raised portions 7 and 8 to form the edges of the channel 11. The ends of these arms 12 are bent inwardly and then flared outwardly to form 90 pairs of upper and lower fingers 13 and 14 respectively, the amount of outward curvature of the lower fingers 14 being greater 95 than that of the upper fingers 13 for a purpose to be hereinafter described.

110

Extending transversely across the raised portion 8 is a groove 15 in which is disposed a strap 16 which connects the central portions of the arms 12. The ends 17 of this strap 16 are bent rearwardly into contact with the outer sides of the arms 12 and are secured thereto by suitable rivets 18, said ends 17 being further extended through openings 19 in the rear side 2 of the casing 1 and then bent inwardly as at 20 to provide a suitable anchoring means. There are a number of ways in which this result may be accomplished, but the above means is the most convenient and is the one which is to be preferably employed.

The inner faces of the raised portions 7 and 8 are provided respectively with alined recesses 21 and 22, said recesses being substantially triangular in shape and having communication with a keyhole 23 disposed in the front side 4 of the casing 1.

The outer face of the rear side 2 is cut away at its upper end as at 24, and in this cut-away portion is secured a plate 25 which extends above the plane of the upper end of said casing and to which is hinged a shell or cover 26, the upper side 27 of which is disposed at an angle to allow the check to be easily inserted in the upper slot 6', as will be hereinafter described. This cover 26 is provided with a suitable handle 26' and is adapted to completely surround the casing 1 to protect the interior thereof from dust, dirt, and the rain.

In operation, the cover 26 is raised and a check 28 is inserted in the slot 6' in the upper end of the casing 1, the upper edge of the front side thereof being provided with a notch 29 to facilitate its insertion. Owing to the fact that the flared ends of the fingers 13 act in the capacity of cams, said fingers are spread when the check 28 is pressed downwardly, the latter then sliding down the channel 11 and into contact with the fingers 14 which are similarly spaced apart by a distance less than the diameter of the check. The cover is then lowered until it is desired to remove the check from the casing, which cannot be done without expanding the fingers 14. This, however, cannot be done without the aid of a key, owing to the fact that the tortuous channel 11 prevents wires or nails from being inserted therein for the purpose of expanding said fingers 14.

To remove the check from the casing, a key 29' is inserted through the keyhole 23, the wing 30 thereof being received in the recesses 21 and 22 in order to bring the notch 31 of said wing 30 into contact with the check 28. By turning the key, the check is forced downwardly, thus expanding the fingers 14 and passing below the same, the flared ends of said fingers assisting in forcing it out through the lower slot 6'. The

lower fingers may be strengthened by placing the screws 5 in contact with the sides thereof, whereby the bending of the fingers takes place at the points of contact.

This invention is particularly adapted to be used in the mining industry, and to this end, the device is shown attached in Fig. 1 of the drawings, to a mine car C. A miner, when he has mined and loaded a car with coal or other mineral, places a check bearing his name or other identification into the casing 1 in the hereinbefore described manner, and the car is forwarded to the weighing master. The weighing master upon receiving the car removes the check from the casing by means of a key with which he is provided, and thus gives credit for the car to the proper party.

From the foregoing it may be seen that a safety mine check holder has been provided from which the checks cannot be lost or substituted by other checks by persons not provided with a suitable key. It may also be seen that the structure shown in the drawings is only one way of carrying out the objects of this invention, and as various changes may be made, I do not wish to be limited to the structure herein shown and described other than that set forth in the appended claims.

I claim:

1. A safety check holder comprising an upright casing having slots in the upper and lower ends thereof and a key hole in one of its sides, said casing having a channel extending vertically therethrough from end to end of the same and in communication with said slots, and means arranged within each end of said casing and disposed adjacent said slots, the means at the upper end of said casing preventing a check within the same from being withdrawn upwardly therefrom, the means at the lower end of said casing preventing said check from being withdrawn downwardly from the same, said check being released upon the operation of a key inserted through said key hole.

2. A safety check holder comprising a casing having slots in the ends thereof and a keyhole in one of its sides, said casing having a channel extending therethrough and in communication with said slots, and resilient fingers mounted in said casing adjacent said slots for retaining a check in the channel therein, said check being released upon the operation of a key inserted through said keyhole.

3. A safety check holder comprising a casing having slots in the ends thereof and a keyhole in one of its sides, said casing having a channel extending therethrough and in communication with said slots, a pair of spaced resilient arms mounted within said casing, the inner sides of said arms

forming the edges of said channel, the ends of said arms being bent inwardly and disposed adjacent said slots to provide pairs of resilient fingers for retaining a check in said channel, said check being released upon the operation of a key inserted through said keyhole.

4. A safety check holder comprising a casing provided with slots in the ends thereof and a key-hole in one of its sides, and having a channel therein, said channel extending longitudinally of said casing from end to end and curving tortuously transversely of the same, and means arranged within each end of said casing and disposed adjacent said slots for retaining a check in said channel, said check being released upon the operation of the key inserted through said key-hole.

15 5. A safety check holder comprising a

casing having slots in the upper and lower ends thereof and a keyhole in one side thereof, raised portions arranged on the inner faces of the front and rear sides of said casing and extending longitudinally of the same, said raised portions being of varying thicknesses throughout their lengths to provide a tortuous channel, the latter communicating with said slots, and pairs of resilient fingers disposed within said casing 30 adjacent said slots for retaining a check in said channel, said check being released upon the operation of a key inserted through said keyhole.

In testimony whereof I hereto affix my 35 signature.

EMANUEL M. SHORTER.
